UNITED STATES PATENT OFFICE.

GEORGE ELLIOT PERRY, OF CHICAGO, ILLINOIS.

TIME-STAMP.

No. 919,072.

Specification of Letters Patent. Patented April 20, 1909.

Application filed October 24, 1904. Serial No. 229,368.

To all whom it may concern:

Be it known that I, GEORGE ELLIOT PERRY, a citizen of the United States, residing at Chicago, in the county of Cook and State of Illinois, have invented new and useful Improvements in Time-Stamp, of which the following is a full, clear, concise, and exact description, reference being had to the accompanying drawing, forming a part of this specification.

My invention relates to time stamps, and has for one of its objects the provision of improved means for winding the motor mechanism of the stamp.

15 The other novel features of my invention will more fully appear from the following description thereof and from the accompanying drawings, in which I have illustrated one way of embodying my invention in a practical device and in which like reference characters are used to designate like parts in the several figures.

Figure 1 is a sectional view of a stamp embodying my invention; Fig. 2 is a view taken 25 on the line 2—2 of Fig. 1, looking in the direction of the arrows, showing a part broken away; and, Fig. 3 is a view of the face of the impression mechanism; and Fig. 4 is a detail perspective of the disconnecting lever.

30 Referring to the drawings by reference characters, an inverted U-shaped frame 1 is provided, the ends of legs 2 of said frame constituting gage parts adapted to engage the surface to be stamped, said frame preferably 35 having side walls 3, 3, adapted to inclose the mechanism of the stamp. Longitudinal slots 4, 4, are formed in the frame 1, said slots being adapted to guide the impression mechanism when said mechanism is moved 40 to make an impression. The impression mechanism is suitably mounted upon a supporting plate 5, the ends of said plate being secured to a yoke 6, said yoke carrying a handle 7. Mounted upon the frame 1 is a 45 tube 8, said tube being adapted to telescope with the handle 7 against the power of the coiled spring 9, preferably disposed within said tube, when the stamp is operated to make an impression, the spring 9 returning 50 the parts of the stamp to their normal positions after an impression has been made. Any suitable inking pad 10 is provided for inking the operative face of the impression mechanism, said pad being adapted to be 55 carried out of the path of the impression mechanism as the same is moved into en-

gagement with the article to be stamped. The pad 10 preferably consists of two members, each member being pivoted to the frame 1 and being adapted to be carried out 60 of the path of the impression mechanism by small rollers 21, 21, carried upon the supporting plate 5 and adapted to engage the edges of the members of the pad 10, as shown in Fig. 1. Any desirable means for 65 inking the face of the impression mechanism may be substituted in lieu of the drop pad above described.

I prefer to use revoluble dies 11 and 12 for indicating the time, said dies carrying pointers or hands, adapted to indicate the time upon stationarily mounted dials 13 and 14, as shown in Fig. 3. The die 11 is adapted to indicate the minute and the die 12 is adapted to indicate the hour, a small revoluble die 15 75 being provided for indicating the forenoon and afternoon of the day. Any suitable mechanism adapted to be relatively moved to indicate time may be substituted in lieu of the dies and dials above described, without departing from the spirit of my invention.

The die 11 is adapted to be continuously driven by a suitable horologic motor mechanism 16 from the arbor 17, upon which the revoluble die 11 is mounted. The arbor 17 85 carries a small gear wheel 18, said gear wheel being adapted to move the revoluble dies 12 and 15 relative to the die 11, to have said dies at all times in proper position for printing the time. The arbors of the revoluble 90 dies and the gearing 19 are preferably disposed between the supporting plate 5 and a sub-plate 20. The day of the month, month and year not having to be changed often, the same is preferably not driven by the motor mechanism 16, but may be stationarily mounted, in any suitable manner, upon the plate 5, as shown in Fig. 3. Any additional impression characters may be suitably mounted upon the plate 5, as shown in Fig. 95 3. Carried by one of the arbors of the revoluble dies is a disk 22, the upper surface of said disk being beveled, as shown in Fig. 1, and being adapted to engage pins 23 carried by the driving arbor of the horologic motor 100 16. The pins 23 are adapted to drive the disk 22. When the impression mechanism is disconnected from the motor mechanism to make an impression, the motor will continue to run, the pins 23 being adapted to 110 engage the beveled surfaces formed upon the disk 22 after an impression has been made,

and are adapted to rotate said disk slightly to compensate for the movement of the motor mechanism while the impression mechanism has been disconnected therefrom in 5 making an impression and thus synchronize the impression mechanism with the motor mechanism. The motor mechanism is mounted between plates 24 and 25, said plates being secured to the table 1 by screws 10 or bolts 26, 26, or in any suitable manner. One end of the main spring of the motor mechanism is secured to a pin 27, the other end thereof being secured to the inner surface of the barrel 28, within which said spring 15 is inclosed. A gear wheel 29 is carried by the pin 27, a similar gear wheel 30 being secured to the barrel 28. The exterior surface of the barrel 28 is preferably screw-threaded, as shown in Fig. 1, a block 31 being adapted 20 to travel said screw-threaded surface, a lug or projection 32 carried by said block being adapted to be engaged by two downwardly extending arms 33, 33, carried by the gear wheel 29. The arms 33, 33, are adapted to 25 rotate the block upon the barrel 28, and to guide said block as it travels the screw-threads formed upon the exterior of said barrel.

The motor mechanism may consist of any 30 suitable construction adapted to be driven by the main spring M, and in the form shown, the small gear wheel 34 is adapted to mesh with the gear wheel 30 mounted upon the barrel 28. A large gear wheel 35 carried 35 upon the pinion of the gear wheel 34 being adapted to mesh with a small pinion 36. A large gear wheel or pinion 37 mounted upon the arbor of the pinion 36, is adapted to mesh with a small pinion 38, the pinion 39 40 carried upon the arbor of the pinion 38 being adapted to mesh with the small pinion 40, upon the arbor of which one of the members 45 of the usual escapement mechanism is mounted, the other member thereof or balance wheel 41 being mounted upon a suitable arbor 42, a hair spring 43 being adapted 50 to coöperate with the escapement mechanism of the motor in the usual manner. Any suitable motor mechanism may be adopted in lieu of that above described.

Centrally disposed within the handle 7, and suitably secured therein, in any suitable manner, against rotation, is a bushing 44, said bushing being shown as riveted to the 55 end of the metal casing or shaft 45. A central aperture is formed in the bushing 44, adapted to be engaged by a shaft 46, said shaft having a spiral groove 47 formed therin, said groove being adapted to be engaged by a pin 48, mounted in the bushing 44, as shown in Fig. 1. The shaft 46 is adapted to rest upon a spur 49, said spur being formed upon the surface of a suitable supporting plate 50, said plate being secured 60 to the plate 25, by screws or rivets 51. The

shaft 46 extends through the frame 1 and carries a pinion or gear wheel 52, said gear wheel being adapted to mesh with the gear wheel 54, carried by a plate 53, the gear wheel 54 meshing with the gear wheel 29 70 carried by the pin 27, to which one end of the main spring is secured. The plate 53 is preferably L-shaped and is loosely carried by the pivot or shaft 27, a small spring 55 being adapted to engage the plate 53 to hold 75 the pinion 54 in engagement with the pinions 52 and 29. Preferably pivoted, slightly eccentrically of the axis of the shaft 27 which is preferably formed integrally with the lever or plate 53 on a stationarily supported eccentric E and adapted to move freely thereon, is a plate 56, said plate having an L-shaped projection 57, said projection being adapted to overlap the periphery of the gear wheel 29 and being disposed 80 within the path of the block 31, as said block traverses the screw-threaded surface of the barrel 28, as shown in Fig. 1. Each of the plates 53 and 56 carries a small projection, to which projections are secured the ends of 85 a spring 58. The spring 58 is of greater strength than the spring 55, the spring 55 being adapted to hold the gear wheel 54 in engagement with the gear wheels 52 and 29, when the spring 58 is dormant, the spring 90 58, when actuated, as hereinafter described, being adapted to carry the gear wheel 54 from engagement with said gear wheels against the power of the spring 55.

The operation of the invention above described is as follows: As the handle 7 is depressed, the pin 48 engaging the groove 47 formed in the shaft 46, will cause the gear wheel 52 carried upon the end of said shaft, to rotate. The gear 52 meshing with the pinion 54, which in turn meshes with the pinion 29, will cause the pinion 29 to be correspondingly rotated, said pinion 29 being mounted upon the shaft 27, to which one end of the main spring of the motor mechanism 105 is secured. As the opposite end of the main spring is secured to the barrel 28, which in turn is secured to the pinion 30, which is adapted to mesh with the gearing of the motor mechanism, it will be seen that power 110 is stored in the main spring and said spring partially wound at each operation of the stamp, or each time the pin 48 traverses the spiral groove 47 formed in the shaft 46, thus 115 rotating the pinion 52. A pawl P, suitably pivoted on a stationary part of the frame (as 25) is provided to prevent the unwinding of the main-spring when the handle 7 rises; and any well-known form of driving-connection; as, for example, a toothed clutch, 120 (not shown) may be used to prevent the backward rotation of the pinion 52 with the rod 46, during the upward movement of the handle. As the main-spring is wound, as 125 above described, by successive operations of 130

the stamp, the block 32 will be carried circumferentially about the barrel 28 by the arms 33, 33, secured to the gear wheel 29, said block rising as it traverses the screw-threaded surface of the barrel. The block 32 is preferably adapted to be carried one-fifth revolution about the barrel 28, at each operation of the stamp, as above described. As the lug 32 carried by the block 31 engages the overhanging projection carried by the plate 56, said plate will be moved upon its pivot one-fifth of a revolution about the barrel 28. The plate 56 being pivoted slightly eccentrically of the axis of the shaft 27, the overhanging projection carried by said plate is adapted to be carried slightly nearer the surface of the barrel 28, as said projection is moved about the barrel by the block 31. It will be seen, therefore, that if the lug 32 should but slightly engage the projection 57 carried by the plate 56, said projection will be carried farther into engagement with the lug 32, as the lug 57 is carried circumferentially about the barrel 28. It will be seen that as the plate 56 is carried by the block 31 about the barrel 28, the projection carried upon said plate, to which the spring is attached, will be separated from the corresponding projection upon the plate 53, to which the opposite end of said spring is attached, the ends of said spring being thus separated and said spring placed under tension. The spring 58 being actuated, as above described, and being stronger than the spring 55, which is adapted to hold the gear wheel 54 in engagement with the gear wheels 52 and 29, will move the plate 53 on its pivot, and will withdraw the gear wheel 54 from engagement with the gear wheels 52 and 29 against the power of the spring 55. When the gear wheel 54 is withdrawn from engagement with the gear wheel 52, as above described, the movable parts of the impression mechanism will be driven by the power stored in the main spring and the operation of the same in making impressions will simply rotate the shaft 46 and the gear wheel 52. As the stamp is wound by successive operations thereof, as above described, the block 32 will travel upward upon the barrel 28, until the winding mechanism of the stamp is thrown out of engagement with the gear wheel 29, as above described. The lug 32 can never pass above lug 57; both by reason of its thickness and on account of the disengagement of the winding mechanism, when lug 32 is near the top of the barrel 28. As the main spring, one end of which is secured to the barrel 28, rotates said barrel in driving the moving elements of the impression mechanism, the block 31 will descend or move downward upon said barrel, until the lug 32 carried upon said block, is carried out of engagement with the overhanging projection 57 carried by the plate 56. When the plate

56 is released from engagement with the projection 32 upon the block 31, the ends of the springs 58 will be drawn together, and said plates will occupy the positions shown in Fig. 2, the gear wheel 54 being thrown into engagement with the gear wheel 52 and the gear wheel 29, by the small spring 55, the operation of the stamp in making impressions again operating to wind or store power in the main spring, as above described. It will thus be seen that the successive operations of the stamp in making impressions, are adapted to automatically wind the motor mechanism. As the power of the main spring is not adapted to be exhausted until the block 31 has traveled to the bottom of the barrel 28, it will be seen that by placing any desirable number of screw threads upon said barrel below the overhanging projection 57 of the plate 56, the power stored in the main spring can be adapted to drive the moving parts of the impression mechanism for any suitable length of time, during which the stamp is not in use, said spring being wound and the block 31 being adapted to travel upward upon the barrel 28 whenever the stamp is actuated to make an impression, until the winding gear thereof is thrown out of engagement with the gear wheel 29, as above described.

I have described the automatic winding device, which I have illustrated herein, with particular reference to the details of said construction, in order that the principles of my invention may be readily understood, and by said detailed description I do not wish to give importance to non-essential parts of my invention, and it will be understood that the construction above described, by which the object of my invention is accomplished, may be changed in many ways without departing from the spirit of my invention and I reserve the right to make such changes as fairly fall within the scope of my invention.

Having described my invention what I claim as new and desire to secure by Letters Patent is:

1. In a time stamp, the combination with an impression mechanism having moving time-controlled impression parts adapted to be used without a platen and depressible in making an impression, of a spring-actuated motor for operating the moving time-controlled impression parts, and means operated by the depression of the impression mechanism for storing energy in said motor.

2. In a time stamp, the combination with a spring-actuated motor, of an impression mechanism having moving time-controlled impression parts operated by said motor and adapted to be moved bodily out of engagement therewith in making an impression, separable means for connecting said impres-

sion mechanism with the motor, and means operated by the movement of the impression mechanism in making an impression for storing energy in said motor.

5 3. In a time stamp, the combination with a motor, of an impression mechanism having moving time-controlled impression parts operated by said motor and adapted to be moved bodily out of engagement therewith 10 in making an impression, separable connecting means between said motor and impression mechanism, permitting the said separation and adapted to synchronize the impression mechanism with the motor when 15 the same are brought into engagement, and means operated by the movement of the impression mechanism in making an impression for storing energy in said motor.

4. In a time stamp, the combination with 20 impression mechanism, having a plurality of movable elements, a spring actuated motor mechanism associated with said movable elements for driving the same, said impression mechanism being movable 25 to and from the surface to be impressed in making an impression, a suitable handle for moving said impression mechanism, and means actuated by the movement of said handle in making an impression, said means 30 being adapted to store power in said spring actuated motor.

5. In a time stamp, the combination with impression mechanism, having moving time controlled parts, of a spring for actuating 35 said parts, a shaft having a worm feed therein associated with said spring, said shaft being adapted to store power in said spring when the stamp is operated to make an impression.

40 6. In a time stamp, the combination with impression mechanism, having moving time controlled parts, of a spring actuated motor for driving said parts, a barrel in which the actuating spring of said motor is inclosed, 45 and means actuated by the movement of the stamp in making an impression, said means being adapted to store power in said spring when an impression is made.

7. In a time stamp, the combination with 50 impression mechanism, having moving time controlled parts, of a spring actuated motor for driving said parts, a suitable barrel within which said spring is inclosed, one end of said spring being secured to said barrel, and 55 means associated with the opposite end of said spring, said means being adapted to store power in said spring when the stamp is actuated to make an impression.

8. In a time stamp, the combination with 60 impression mechanism, having moving time controlled parts, of a spring actuated motor for driving said parts, a suitable barrel within which said spring is inclosed, means actuated by the movement of the stamp in mak-

ing an impression for storing power in said 65 spring, and means for automatically throwing said first mentioned means out of and into operative engagement with said spring.

9. In a time stamp, the combination with 70 impression mechanism, having moving time controlled parts, of a spring actuated motor for driving said parts, suitable means actuated by the movement of the stamp in making an impression for winding said spring, and means controlled by said spring for 75 throwing said first mentioned means out of operative engagement therewith when said spring is sufficiently wound.

10. In a time stamp, the combination with 80 impression mechanism, having moving time controlled parts, of a spring actuated motor for driving said parts, means actuated by the movement of the stamp in making an impression for storing power in said spring, and means controlled by said spring for 85 throwing said first mentioned means into operative engagement therewith when the power of said spring is nearly exhausted.

11. In a time stamp, the combination with 90 impression mechanism, having moving time controlled parts, of a spring actuated motor for driving said parts, a barrel within which said spring is inclosed, one end of said spring being secured to said barrel, a pin centrally 95 disposed within said barrel, the opposite end of said spring being secured to said pin, means operated by the movement of the stamp in making an impression for rotating said pin, whereby power is stored in said spring, and means associated with said pin 100 for throwing said first mentioned means out of operative engagement therewith after sufficient power has been stored in said spring.

12. In a time stamp, the combination with 105 impression mechanism, having moving time controlled parts, of a spring actuated motor for driving said parts, a screw threaded barrel in which said spring is inclosed, means actuated by the movement of the stamp in 110 making an impression for storing power in said spring, and means adapted to travel in the screw threaded portion of said barrel, said means being adapted to disconnect said 115 first mentioned means from operative engagement with said spring when sufficient power has been stored therein, and being adapted to throw said part into operative engagement therewith when the power of said spring has been partially exhausted.

120 In witness whereof, I have hereunto subscribed my name in the presence of two witnesses:

GEORGE ELLIOT PERRY.

Witnesses:

E. A. OLSEN,
M. R. ROCHFORD.

It is hereby certified that in Letters Patent No. 919,072, granted April 20, 1909, upon the application of George Elliot Perry, of Chicago, Illinois, for an improvement in "Time-Stamp," an error appears in the printed specification requiring correction, as follows: Page 2, lines 79 and 80, the words "which is preferably formed integrally with the lever or plate 53" should be stricken out and inserted after the reference-letter "E" in line 81, as now numbered; and that the said Letters Patent should be read with this correction therein that the same may conform to the record of the case in the Patent Office.

Signed and sealed this 11th day of May, A. D., 1909.

[SEAL.]

E. B. MOORE,
Commissioner of Patents.
